UNITED STATES PATENT OFFICE

DANA E. HARDING, OF MELROSE, MASSACHUSETTS, ASSIGNOR TO HARDING ENGINEERING COMPANY, OF EAST BOSTON, MASSACHUSETTS, A CORPORATION OF MASSACHUSETTS

SHANKING MACHINE

Application filed October 11, 1928. Serial No. 311,837.

My present invention relates to leather working machines, and more particularly to an improved shanking machine.

In the manufacture of leather from hides or skins, a considerable amount of merchantable leather is wasted because of the inability of the present processes or machines employed to smooth out or take care of the shanks of the hides or skins. With the machines in employment at the present day, the shanks are of course worked upon but in such a direction as to stretch the same out and place longitudinal wrinkles therein; which wrinkles, as the process of manufacture advances, become more and more pronounced until, in the finished skin, the shanks are, in reality, nothing but waste leather and in the utilization of the hides or skins in the art the cutter invariably cuts off the shank and it is thrown away as waste. It is a fact, however, that the shanks contain a considerable area of possible merchantable leather and I have, in my present invention, devised a machine for processing the hides or skins, and particularly the shank portion thereof in such a way that the shank is smoothed out in two directions practically perpendicular to the longitudinal axis of the shanks. The result is that the shank is smoothed out at such a point in the manufacture of the leather from the hides or skins that it is not thereafter subjected to any distorting action on the part of other machines.

Consequently, as the process of making the leather advances, the shank remains smooth and in the finished product there is an appreciable amount of visible merchantable leather which is utilized in the art and which will not be wasted.

In carrying out my invention, I utilize a pair of spaced corrugated rolls rotating in opposite directions and associate with said rolls a V-shaped anvil which is automatically movable into and out of position between the two rolls above referred to. The movement of the anvil into and out of position between the rolls is relatively slow and the operator will have ample time between each stroke for the accurate placing of the shank portion of the hide or skin on the anvil. The rolls act on the shank portion of the hide or skin in

such a way as to smooth out from practically a central line extending throughout the length of the shank and perpendicular thereto and smooth out any wrinkles that may be in such shank portion, and the action of the rollers continues during the moving of the anvil into position between such rolls and until such anvil moves out of such position. 55

The object of my invention, therefore, is an improved shanking machine. 60

In the accompanying drawings illustrating a preferred embodiment of my invention,

Fig. 1 is a side elevation;

Fig. 2 is an end elevation; and

Fig. 3 is a fragmentary plan view of the table top and anvil showing the shank portion of a hide or skin in position thereon. 65

Referring to the drawings, 10 designates a table or bench supported by legs 11 at a proper height from the floor and such table 10 is provided with a rectangular slot 12 of suitable length and breadth. To the under surface of the table 10 and adjacent to the ends of the rectangular slot 12 are secured, by bolts 13, bearing brackets 14 defining parallel guideways in which are slidably mounted the parallelly arranged bars 15. The bars 15 at their upper ends are secured to a substantially triangular anvil 16 the apex of the anvil being rounded and uppermost, 70 as indicated at 17. To the lower ends of the bars 15 is secured a cross bar 18 and pivotally attached to the bar 18 is the upper end of a link 19. On the floor of the shop or room in which the device is located and directly beneath the pivotal connection of the link 19 with the bar 18 is a bearing member 20 and pivotally attached to such bearing member is the lower end of the link 21. The links 19 and 21 are pivotally connected together 75 at 22 and also on such pivotal connection is pivotally mounted one end of a connecting rod 23. The connecting rod 23 is pivotally attached to a crank pin 24 on a face plate 25, that is attached to the driving shaft 26 of a motor or other prime mover 27. Rotary movement of the shaft 26 of the motor 27 will cause a reciprocatory motion of the connecting rod 23 and, therefore, a movement of the links 19 and 21 from the dotted position 80

85

100

shown in dot and dash lines, shown in Fig. 1, to the full lines shown therein, thereby causing a reciprocatory motion of the anvil 16, moving the same from its lowermost to its 5 uppermost position.

Mounted on top of the table 10 and secured thereto by bolts 28, is a substantially U-shaped frame member comprising uprights 29 and a transverse member 30 connecting same 10 at their top ends. Secured to the transverse member 30 by bolts 31 and spaced apart from, though in alinement with each other, are bearings 32. In one of such bearings 32 is rotatably mounted a shaft 33 provided with a 15 bevelled pinion 34 on its inner end, which meshes with a bevelled pinion 35 on the drive shaft 36 of a motor 37, the motor 37, therefore, acting to rotate the shaft 33 in the proper direction. In the other of the bearings 32 20 is secured a shaft 38. Pivotedly mounted on the shafts 33 and 38 and extending downwardly therefrom so as to terminate at one side of the rectangular slot 13 is an H-shaped frame 40. Alined bearings are formed in 25 the lower end of the H-shaped frame 40 and in such bearings is rotatably mounted a shaft 41. Secured to the shaft 41 is a corrugated roller 42 and adjacent to one end of such corrugated roll 42 is a cylindrical 30 collar 43 that is adapted to engage with a track 44 on one end of the anvil 16. Secured to one end of the shaft 41 is a grooved pulley 45 that is in alinement with the grooved pulley 46 secured to the shaft 33 and over the 35 pulleys 45 and 46 runs an endless belt 47 and by means of which power is transmitted to the shaft 41. Also pivotedly mounted on the shafts 33 and 38 is a second H frame 48 and at the lower end of such H frame 48 are alined 40 bearings in which is rotatably mounted a shaft 49. On such shaft 49 is mounted a corrugated roll 50 which is located on the opposite side of the anvil from the corrugated roll 42. Adjacent to one end of the 45 roll 50 and on the shaft 49 is a collar 51 which engages with a track 52 on the anvil 16. The relation of the diameters of the rolls 42 and 50 with respect to the diameters of the collars 43 and 51 is such that the rolls 42 50 and 50 are always maintained at a fixed distance from the surface of the anvil 16. Secured to one end of the shaft 49 is a grooved pulley 58 which is in alinement with a grooved pulley 59 secured to the shaft 33 and running 55 over the grooved pulleys 58 and 59 runs an endless belt 60 that is crossed so as to insure that the roller 50 will rotate in the opposite direction from the rotation of the roll 42. The H-shaped frames 40 and 48 are drilled 60 to receive a shaft 53, such shaft being threaded on its ends and each threaded end being supplied with a hand wheel 54. Between each hand wheel 54 and the corresponding H frame 40 or 48 is located a coil spring 55 and 65 by properly adjusting the hand wheels 54, the

tension exerted by the springs 55 on the H frames may be adjusted at will. The anvil 16 is adapted to receive the shank portion 58 of a hide 57 in the position shown in Fig. 3.

The operation of my improved device is as follows. The tension of the springs 55 having been adjusted to the right degree and power being turned on to the motors 27 and 37, the operator will, at a time when the anvil 16 is in its lowermost position, slide the shank 56 of a hide 57 over the rectangular opening 12 and in such position that the shank 56 will lie along the length of the anvil 16 when such anvil is automatically raised by the links 19 and 21. As the anvil 16 moves upwardly, it moves between the corrugated rolls 42 and 50, which, as will be obvious, exerts a smoothing out or ironing effect on the shaft 56 so as to stretch the same in lines substantially perpendicular to the longitudinal axis of such shank. The anvil 16 moves upward to its full extent and then automatically moves downward, and during both such movements, the rolls 42 and 50 are acting thereon. When the anvil 16 has reached its lowermost position, the operator removes the shank 56 from position thereon and repeats the operation above described indefinitely.

While I have necessarily described the preferred embodiment of my invention somewhat in detail, it is to be understood that I may vary the size, shape, and arrangement of parts within wide limits without departing from the spirit of the invention.

Having thus described my invention, what I claim as new is:

1. In an improved shanking machine the combination of a framework, a pair of pivotedly mounted frames mounted thereon, and extending downwardly therefrom, a pair of rolls rotatably mounted in said pivoted frames, means for rotating said rolls in opposite directions and at the same speed, means for resiliently holding such pivoted frames in operative position, a wedge-shaped anvil, and means for imparting a reciprocatory movement thereto into and out of position with relation to the corrugated rolls.

2. In a shanking machine, the combination of a pair of corrugated rolls, means for rotating the same in opposite directions and at the same speed, a wedge-shaped anvil co-operating with said rolls, means for imparting a reciprocatory motion to said anvil to move the same into and out of operative position with respect to the rolls, and means associated therewith and with the rolls for preventing actual engagement of the anvil surface by the rolls.

3. In a shanking machine, the combination of a worktable provided with a rectangular perforation, guideways secured to said table at each end of the rectangular opening, a triangular anvil movable through said opening, means on said anvil engaging with said guide-

ways to constrain the anvil to move in a predetermined path, means for imparting a reciprocatory movement to said anvil, and corrugated rolls located above the table and operatively associated with said anvil.

5 In testimony whereof, I have signed my name to this specification.

DANA E. HARDING.
